(57) **CLAIM**

The ornamental design for an air scoop, as shown and described.

DESCRIPTION

FIG. 1 is a perspective view of the air scoop showing the new design;

FIG. 2 is a front elevation thereof;

FIG. 3 is a rear elevation thereof;

FIG. 4 is a top plan view thereof;

FIG. 5 is a bottom plan view thereof;

FIG. 6 is a left side view thereof, the right side view being a mirror image of the left side view; and,

FIG. 7 is a sectional perspective view thereof in which a top portion is cut away.

The broken lines in FIGS. 2, 3, 5, 6, and 7 show portions of the air scoop that form no part of the claimed design.
